UNITED STATES PATENT OFFICE.

JULIUS DORNETH, ~~OF~~ KONRADSHOHE, NEAR TEGEL, GERMANY.

MATRIX-SETTING AND TYPE-BAR-CASTING MACHINE.

Application filed April 8, 1924. Serial No. 705,112.

To all whom it may concern:

Be it known that I, JULIUS DORNETH, residing at Konradshohe, near Tegel, Falkenhorststrasse 7, State of Prussia, Germany, a citizen of Germany, have invented certain new and useful Improvements in Matrix-Setting and Type-Bar-Casting Machines, of which the following is a specification.

This invention relates to justifying devices for matrix setting and type-bar casting machines having circular spacing means.

The invention consists of the novel construction and combination of parts to be hereinafter more fully described and claimed.

In the accompanying drawing a constructional example of the invention is shown, in which.

Fig. 1 is a section through the composing points on line A—B of Fig. 3,

Fig. 2 a section on line C—D of Fig. 3 and

Fig. 3 a plan view of the composing point, all parts not required for understanding the drawing being omitted.

It is known that for justifying, more particularly in the case of long matrix bars, two superposed circular spacing members *b*, *c* are used, the non-rotatable parts of which are connected by a bridge member *m*, which terminates at the top in an arm *a* with a hook *n*. The spacing members with the matrices are suspended by means of the said hook on guide wires *o*. The rotatable circular wedges of the spacing members have no hole in the middle and are each provided at their periphery with a notch *d*, *e* with which they embrace round bars *f*, *g* when they come into the composing position. The bars are capable of being rocked in the direction of the arrows (Fig. 1) round the centre of the circular spacing members and in this rocking movement carry the circular members round with them, the line being justified by this means. After the line has been cast, the bars *f*, *g* return to their former position and rock the circular members in a corresponding manner.

The motion of the round bars *f*, *g* may be imparted to them in any suitable manner, for instance, as shown in Figs. 2 and 3, by means of the rack *l* hitherto used for turning the spacing members by means of pinions *i*, *k* mounted on the square shafts for the said members. In the new arrangement the pinions *i*, *k* are mounted on special shafts,

as the square are no longer used, and are provided with arms *r*, *s*, at the ends of which the round bars *f*, *g* are journaled. On the rack *l* moving upwards in a known manner, after the machine has been put in motion, the round bars *f*, *g* move upwards and effect the justifying of the line.

The new justifying device is specially suitable for machines, in which matrices travel in a closed path. It has hitherto not been possible to construct such machines with circular spacing members, as the arrangement of the square shafts and the way in which they are journaled prevented the line, after casting, being deposited in the direction of motion of the matrix when setting up the type. Owing to the square shafts being done away with and the suspension of the circular spacing on wires, this difficulty is overcome.

Having now particularly described and ascertained the nature of my said invention and in what manner the same is to be performed, I declare what I claim is:

1. A justifying device for matrix setting and type-bar casting machines with a spacing device, comprising in combination a plurality of circular spacing wedges and means in engagement with said circular spacing wedges at the peripheries thereof for turning the spacing wedges.

2. A justifying device for matrix setting and type-bar casting machines with a spacing device, comprising in combination a plurality of circular spacing wedges, notches in the periphery of the said wedges, round bars capable of engaging in the said notches and means for causing the said bars, when engaged in the said notches, to rock with the wedges about the axes of the latter, as set forth.

3. A justifying device for matrix setting and type-bar casting machines with a spacing device, comprising in combination a plurality of rotatable circular spacing wedges, a non-rotatable part and an upwardly extending arm on the non-rotatable part for suspending the said device to a guide-wire on the machine and means, whereby the power required for turning the said circular spacing wedges is applied at the periphery of the said circular wedges, as set forth.

In testimony whereof I hereunto affix my signature.

JULIUS DORNETH.
